UNITED STATES PATENT OFFICE.

FREDERICK D. MILLER, OF CHICAGO, ILLINOIS, ASSIGNOR OF ONE-HALF
TO ALFRED STEFFEN, OF SAME PLACE.

CURLING-IRON.

SPECIFICATION forming part of Letters Patent No. 429,279, dated June 3, 1890.

Application filed April 16, 1889. Serial No. 307,493. (No model.)

To all whom it may concern:

Be it known that I, FREDERICK D. MILLER, of Chicago, in the county of Cook and State of Illinois, have invented certain new and useful Improvements in Curling-Irons; and I do hereby declare that the following is a full, clear, and exact description thereof, reference being had to the accompanying drawings, and to the letters of reference marked thereon, 10 which form a part of this specification.

This invention relates to a novel construction of curling-iron of the kind wherein a cylindric metal mandrel is provided with a handle at one end, and which is used by heating the mandrel and curling the hair about the same.

This invention embraces a novel construction of handle whereby the transmission of heat from the mandrel to the handle is materially decreased, and also embraces a novel construction and arrangement of the spring-clasp and its spring; and it consists in the novel features of construction and combinations of parts hereinafter fully described, and 25 pointed out in the appended claims.

In the drawings, Figure 1 is a side elevation of a curling-iron embodying my invention. Fig. 2 is a vertical longitudinal sectional view of the same. Fig. 3 is an enlarged vertical transverse sectional view on the line 3 3 of Fig. 2. Figs. 4, 5, and 6 are views of a modified form of construction embodying my invention. Fig. 7 is a plan view of a portion of my invention, and illustrating the hinge of the spring-clasp and its spring. 35

In said drawings, A is a mandrel, which is hollow and of cylindric form.

B is a hollow handle of cylindric form and corrugated longitudinally. The handle B is 40 open at both ends, and the mandrel A is inserted and secured in one end thereof. It will be noted that a plurality of small openings b b are thus provided between the adjacent ends of the mandrel and the handle by 45 reason of the irregular contour of the handle.

C is a spring-clasp arranged upon the mandrel, and is provided at its rear with an outwardly-deflected portion c, having a finger-button c', which forms an operating-handle 50 for said clasp. The clasp C is held by means

of a depression a, formed in the mandrel A, into which a lug or projection c² on the spring-clasp is adapted to enter.

D is a wire spring comprising a cross-piece d and downwardly-deflected arms d' d'. The 55 cross-piece d rests in a slot c³ in the spring-clasp forward of its pivotal point, and the arms d' d' pass downwardly on either side of the mandrel and have their ends secured in two of the openings b b.

E is a heating-iron provided at one end with a connecting-piece e and a thumb-piece e'. The said thumb-piece is provided with a hub e², having an annular groove e³ and a cut-away portion e⁴. 60

Upon the rear end of the handle B an inwardly-projecting lug b² is formed. It is obvious that the iron E can be passed through the handle from the rear and introduced into the mandrel. The operator then brings the 70 cut-away portion e⁴ opposite the lug b² and pushes the hub e² in until the groove e³ is in line with said lug. By giving the thumb-piece e' a turn the said lug b² will be caused to enter the annular groove e³, and thus hold 75

or lock the iron against displacement. The object in corrugating the handle, as will be readily understood, is to prevent the said handle from becoming too highly heated, the openings b formed between the corrugations in the handle and mandrel allowing a free circulation of the air within the same for the above purpose. The said corrugations also provide a convenient handle that can be firmly grasped when using the device. It 80 will be manifest that the corrugations can be made otherwise than straight—as, for instance, they could be arranged spirally and still serve the ends of this invention. 85

In Figs. 4, 5, and 6 I have illustrated modified forms of devices embodying my invention by which the heating-iron is held within the mandrel. In Fig. 4 the hub e² is made large enough to fit tightly within the end of the handle and be held in place by friction. 90 In the device illustrated in Fig. 5 the connecting-piece e between the hub and the iron is curved sufficiently to engage the insides of the handle, and thus hold the said iron in place by the friction between said connect- 95 100

ing-piece and the handle. In Fig. 6 the hub e^2 is held in frictional contact, as shown in Fig. 4, but the thumb-piece e' is reduced to the same or smaller diameter than the hub e^2 . This is a very desirable construction, as spaces b' , similar to the spaces b , are opened at this end of the handle B, and thereby permit the free passage of a current of air directly therethrough.

10 I claim as my invention—

1. A curling-iron comprising a mandrel and a hollow corrugated handle, substantially as described.

15 2. A curling-iron comprising a mandrel and a hollow corrugated handle, said mandrel secured at one end within the end of the said handle, substantially as described.

20 3. A curling-iron comprising a hollow mandrel secured at one end within the end of a hollow corrugated handle, and a heating-iron adapted to be introduced into the mandrel from the rear through said corrugated handle, said iron being provided on its rear end

with an engaging device to hold it in place, substantially as described.

25

4. The combination, with a curling-iron comprising a corrugated handle, a mandrel secured at one end within said corrugated handle, and a heating-iron, of a clasp arranged upon and pivoted to said mandrel, 30 said clasp being provided with a lug adapted to enter a depression in said mandrel, and a spring secured to said clasp and having arms which are arranged on either side of the said mandrel and are secured within openings 35 formed between the corrugations in said handle and the end of the mandrel, substantially as described.

In testimony that I claim the foregoing as my invention I affix my signature in presence 40 of two witnesses.

FREDERICK D. MILLER.
